[57] **CLAIM**

The ornamental design for a cursor for computer display terminal, as shown and described.

DESCRIPTION

FIG. 1 is a perspective view of a cursor for computer display terminal showing my new design;

FIG. 2 is a top plan view on a reduced scale;

FIG. 3 is a side elevational view thereof on a reduced scale, the opposite side being a mirror image; and

FIG. 4 is an end elevational view thereof on a reduced scale, as seen from the right of FIG. 3.

FIG. 1
